UNITED STATES PATENT OFFICE.

ARTHUR KITSON, OF PHILADELPHIA, PENNSYLVANIA, ASSIGNOR TO THE KITSON HYDROCARBON HEATING AND INCANDESCENT LIGHTING COMPANY, OF SAME PLACE AND CHARLESTON, WEST VIRGINIA.

SUSPENSION APPARATUS.

SPECIFICATION forming part of Letters Patent No. 632,500, dated September 5, 1899.

Application filed March 20, 1899. Serial No. 709,811. (No model.)

To all whom it may concern:

Be it known that I, ARTHUR KITSON, a subject of the Queen of Great Britain, and a resident of Philadelphia, county of Philadelphia,

5 State of Pennsylvania, have invented certain new and useful Improvements in Suspension Apparatus, (Case No. 32,) of which the following is a specification.

My invention relates to suspension apparatus provided with flexible connections capable of transmitting a supply of fluids under pressure, and more specifically consists of an improved form of jointed suspension apparatus for oil-burning lamps, together with an arrangement of flexible tubing attached thereto for the purpose of supplying oil to the lamp and so arranged that it shall not be broken or bent, so as to close the passage-way through the tubing when the jointed suspension apparatus is shifted in its position to raise or lower the lamp.

Where a series of oil-burning lamps—such, for instance, as those burning the vapor of oil under pressure in conjunction with an incandescent mantle—are used to light rooms or sheds having high ceilings, it is necessary to suspend said lamps at a height beyond the reach of the lamp-trimmer. To avoid the necessity of said lamp-trimmer carrying around a step-ladder, it becomes desirable to provide means for raising and lowering said lamps so that they may be dropped down within reach of a man standing on the floor or drawn up to their proper height. To accomplish this without breaking or bending the fine flexible metal tube through which oil is supplied under a pressure of forty or fifty pounds, I have designed an improved form of suspension apparatus for supporting both said lamp and the tube.

The preferred form of construction embodying my invention is illustrated in the accompanying two sheets of drawings, in which—

Figure 1 is a side elevation of the apparatus with the lamp in its elevated position. Fig. 2 is an end elevation of same. Fig. 3 is an enlarged detail plan view of one of the coils of tubing. Fig. 4 illustrates a slightly-modified form of apparatus, the dotted lines rep-

resenting the position of the same when lowered. Fig. 5 is an enlarged detail showing a side view of one of the spools employed in this modified construction.

Throughout the drawings like reference figures refer to like parts.

From a ceiling or roof 1 the entire apparatus is suspended by means of the eyebolt 2, to which the first link 3 of the jointed suspension apparatus is pivoted. A line of metal tubing 4 runs along the ceiling to said point of suspension, at or near which point it is coiled into a spiral 5 of one or more turns. The tubing is then attached in any convenient way to the various links of the jointed supporting apparatus by means of bands 6, 65 &c., if desired. The free end of the link 3 is normally supported by the cord or chain 7 running over the pulley 8, also mounted on the roof or ceiling, the cord extending down to a point within the reach of a person standing on the floor and there fastened in any suitable way. (Not shown.) The second link 9 is pivoted to the free end of the first link 3 in any convenient manner, and the tubing 4 is coiled into a second spiral 10 at or near the joint between the two links. The tubing continues along the second link 9 to the lamp or other consuming device 11.

In the modified construction shown in Fig. 4 the coil 5 is formed around a spool 12, 80 mounted on a projection 2^a from the eyebolt 2, and the coil 10 is similarly formed about the spool 13, mounted on a projection 3^a from the free end of the link 3. The centers of these spools are approximately coincident 85 with the axes of the joints between the various sections of the suspension apparatus.

The mode of operating my invention is as follows: The lamp is normally in the position shown in Figs. 1, 2, and 4 in full lines. When the lamp is to be trimmed, the operator loosens the cord 7 and allows it to reeve over the pulley 8, thus lowering the free end of the link 3, the whole apparatus assuming the position shown in dotted lines in Fig. 4. 95 This brings the lamp down within reach of the operator. When the links are swung, as shown by the arc in broken lines in Fig. 4,

the spiral 5 winds up a trifling amount and the spiral 10 unwinds a trifling amount. This permits the tubing to accommodate itself to the changed position without making any sharp bend, which would break it or partly close it. Thus, for instance, if a three-coil spiral is employed, as indicated in Fig. 3, the coil 5 would, roughly speaking, be reduced only one-twelfth of its radius and the coil 10 10 would be increased in radius one-twelfth. This would evidently produce but a slight change in the curvature, and that slight change would be equal throughout the entire spiral. The spools 12 and 13 help to center 15 the spirals coincidently with the joints of the suspension apparatus, and thus protect them from unequal expansion and contraction, also from any excess of bending strain at any one point.

20 It is evident, of course, that various changes could be made in the details of construction shown without departing from the spirit and scope of my invention so long as the relative arrangement of parts shown in the drawings 25 or the principle of operation described in the specification is preserved. Links of different lengths may be employed, and a greater or less number might be used than that shown. Other means for raising and lowering the 30 lamp might be substituted for the cord and pulley shown, and the point of attachment of the flexible tubing to the fixed support might be varied; but such modifications I consider mere changes in form and not in 35 substance and still within the scope of my invention.

Having therefore described my invention, what I claim as new, and desire to protect by Letters Patent, is—

40 1. The combination of the jointed suspension apparatus and the flexible tube extending along the same and coiled into a spiral at or near each joint in the suspension apparatus.

2. The combination of the fixed support, the 45 jointed suspension apparatus consisting of a plurality of links flexibly joined together, one end of such jointed suspension apparatus being attached to the fixed support, the lamp suspended from the other end of the jointed

suspension apparatus, and a flexible tube extending along the apparatus from the fixed support to the lamp. 50

3. The combination of the jointed suspension apparatus consisting of a plurality of links, the lamp suspended from the last link, 55 and the flexible tube extending along the apparatus to the lamp, said tube being attached to the suspension apparatus and coiled into spirals at or near the joints thereof.

4. The combination of the support, the link 60 of the suspension apparatus pivoted to said support, the pulley attached to the support and the cord attached to the free end of the above-mentioned link and running over said pulley, the lamp swung from the free end of the link, and the flexible tube extending along said link to the lamp and coiled into a spiral at either end of said link. 65

5. The combination of the fixed support, the lamp, movable means for suspending said 70 lamp from said support, and the flexible tube attached to the lamp and to a fixed point of support and coiled into spirals adapted to expand and contract to accommodate the movements of the lamp. 75

6. The combination of the fixed support, the jointed suspension apparatus consisting of a plurality of links flexibly joined together, one end of such jointed suspension apparatus being attached to the fixed support, the lamp suspended from the other end of the jointed suspension apparatus, a flexible tube extending along the apparatus from the fixed support to the lamp, together with means for raising and lowering the last link in the jointed 80 suspension apparatus. 85

7. The combination of the jointed suspension apparatus, the spools mounted on the same near the joints thereof, and the flexible tube extending along the suspension apparatus and coiled around said spools. 90

Signed by me at New York, N. Y., this 11th day of March, 1899.

ARTHUR KITSON.
